CLAIM

The ornamental design for a portion of a medical device as shown and described.

DESCRIPTION

FIG. 1 is a top perspective view of a portion of a medical device showing our new design;

FIG. 2 is a bottom perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof;

FIG. 8 is a bottom plan view thereof; and,

FIG. 9 is an enlarged view of a portion thereof.

The dash-dot-dash broken lines in FIG. 1 illustrate the perimeter of a portion of the medical device that is shown enlarged in FIG. 9. The broken lines depict portions of the medical device that form no part of the claimed design.
